US00D943928S

(12) **United States Design Patent** (10) **Patent No.:** **US D943,928 S**
(45) **Date of Patent:** **** Feb. 22, 2022**

(54) **SHOE**

(71) Applicant: **adidas AG**, Herzogenaurach (DE)

(72) Inventor: **Nic Galway**, Herzogenaurach (DE)

(73) Assignee: **adidas AG**, Herzogenaurach (DE)

(**) Term: **15 Years**

(21) Appl. No.: **29/732,834**

(22) Filed: **Apr. 28, 2020**

Related U.S. Application Data

(63) Continuation of application No. 29/665,454, filed on Oct. 3, 2018, now Pat. No. Des. 885,720.

(57) **CLAIM**

The ornamental design for a shoe, as shown and described.

DESCRIPTION

FIG. 1 is a front medial perspective view of a shoe.

FIG. 2 is a medial side view of the shoe of FIG. 1.

FIG. 3 is a lateral side view of the shoe of FIG. 1.

FIG. 4 is a front view of the shoe of FIG. 1.

FIG. 5 is a rear view of the shoe of FIG. 1.

FIG. 6 is a top view of the shoe of FIG. 1; and,

FIG. 7 is a bottom view of the shoe of FIG. 1.

The broken lines indicate unclaimed portions of the shoe, and form no part of the claimed design.

1 Claim, 7 Drawing Sheets
